Primary Examiner — John Windmuller(57) **CLAIM**

The ornamental design for a handle, as shown.

DESCRIPTION

FIG. 1 is a front elevational view of a handle showing my new design;

FIG. 2 is a rear elevational view thereof;

FIG. 3 is a right side elevational view thereof, the left side elevational view being a mirror image of FIG. 3;

FIG. 4 is a top plan view thereof;

FIG. 5 is a bottom plan view thereof;

FIG. 6 is a perspective view of my new design as embodied in an umbrella handle; and,

FIG. 7 is a perspective view of my new design as embodied in a building door handle.

The broken lines in the figures depict both portions of the handle and environment that form no part of the claimed design.
